OUTBOARD BRAKE FOR RAILWAY CAR TRUCKS

Alfred H. Oelkers, Chicago, Ill., assignor to American Steel Foundries, Chicago, Ill., a corporation of New Jersey

Application March 7, 1935, Serial No. 9,705

40 Claims. (Cl. 188—58)

My invention relates to railway brake equipment and its object, generally speaking, is the provision of a special form of brake for stopping or reducing the speed of railway cars by retarding the rotation of car wheels without applying friction to that portion of the wheel which runs on the rail and carries the weight.

The usual type of braking equipment for railway cars, that is, a metallic brake shoe frictioned on the rim of the wheel, has been a source of considerable difficulty in the maintenance of wheels. To carry heavy loads on the steel rail it is essential to have a comparatively hard metal in the rim of the wheel and metal having the proper physical properties for this purpose is usually softened and otherwise damaged by the heat of brake shoe friction and often small cracks formed on the surface of the wheel develop into wheel fractures.

An object is to provide a brake of an outboard design, i. e., a design in which the brakes are located outwardly of the wheels, thus facilitating application and inspection of wearing parts.

Another object is to mount an auxiliary wheel or drum adjacent the usual wheel hub mounting, thus providing a means of brake application independent of the tread portion of the wheel which is commonly used for that purpose.

Yet another object of the invention is to provide such a drum or auxiliary wheel of such design and proportions as will absorb and dissipate the considerable quantities of heat energy developed when the brakes are applied, and at the same time prevent the loosening of the hub fit which otherwise might occur as such heat is generated.

A still further object is to design the said auxiliary wheel or drum structure so that its rim portion may be permitted to expand normally as the temperature is raised by the application of brakes without impairing the original press fit of the hub portion upon the axle.

A still further object of this invention is to provide a supporting structure for such braking equipment which will maintain concentric relation between the said drum and the shoes applied thereto for braking purposes.

With these and various other objects in view, the invention may consist of certain novel features of construction and operation as will be more fully described and particularly pointed out in the specification, drawings and claims appended hereto.

Figure 1 is a fragmentary side elevation of a four-wheel truck structure, passenger type, em-

bodying the invention and showing one wheel and axle assembly thereof. Only one end of the wheel and axle assembly is shown in the drawings and only one end of the truck structure inasmuch as the truck as a whole is bi-symmetrical in form and the parts not shown are symmetrical with those shown; 5

Figure 2 is a vertical sectional view taken substantially in the plane indicated by the line 2—2 of Figure 1; 10

Figure 3 is a top plan view of the structure shown in Figures 1 and 2;

Figure 4 is a vertical sectional view taken substantially in the plane indicated by the line 4—4 of Figure 1 and showing in detail the method of connecting one end of the brake carrier member to a truck frame member; 15

Figure 5 is a horizontal sectional view taken substantially in the plane indicated by the line 5—5 of Figure 1; 20

Figure 6 is a fragmentary side view in elevation of a friction bearing design of truck to which is applied my novel form of brake equipment; and

Figure 7 is a vertical sectional view taken substantially in the plane indicated by the line 7—7 of Figure 6. 25

Describing more in detail one form of structure embodying this invention, the truck side frame member 2 is one of a pair of identical members connected by the usual bolster or transom (not shown) upon which the weight of the car body is carried. The side frame 2 has the pedestal 4 associated with the journal portion of the axle 6 forming a part of the wheel and axle assembly 8 through a structure to be hereafter described in more detail. The truck structure shown is of a type commonly known as an equalized truck and has the equalizer 10 provided at its respective ends with the arcuate bottom surface 12 fitting within the complementary groove 13 formed between the lugs 14 and 16 on the top of the journal portion 18 of the brake carrier 20. The spring seat member 22 is secured upon the equalizer 10 by the bolt and nut 40 structure 24. At its inner edge the spring seat 22 has the eye 26 formed on the flange 28 providing a means of connection with the inner end of the brake carrier 20. The usual spring 30 is interposed between the equalizer spring seat 22 45 and the spring seat 32 integrally formed on the under side of the side frame member 2. 50

The wheel and axle assembly shown is a well known type of roller bearing design although the exact structure of this roller bearing wheel and

axle assembly is no part of this invention because I have so designed this structure that it may also be used with a friction type of wheel and axle assembly. In the structure shown, the 5 inner axle 6 has the journal portion 34 defined outwardly by the annular collar 36 at the end of the axle and inwardly by the shoulder 38. Sleeved around the inner axle is the outer axle or housing 40 and between the two axles is 10 mounted the roller bearing axle, generally designated at 42, which is secured in place by abutment inwardly against the shoulder 44 of the housing 40 and outwardly against the sleeve 46 which may be pressed or shrunk on the inner axle 6. The closure plate 48 seals the bearing cavity and is secured to the housing 40 by a series 15 of bolts 50. The wheel 8 may be pressed upon the housing and secured in position thereon against the shoulder 52. An auxiliary wheel or drum 54 may be thereafter pressed upon the housing 40 and secured thereon in abutment against the wheel 8.

The auxiliary wheel or drum 54 is of the general shape of a truncated cone having the rim portion 55, the plate portion 57 and the hub portion 59. The rim portion 55 and the hub portion 59 are of relatively heavy section and the plate portion joining them is comparatively flexible. The result is that when the rim portion 30 55 is heated up by the application of brakes and tends thereby to expand, the effect is to produce a slight flattening of this truncated cone structure. In other words, the rim portion tends to be drawn closer to the hub portion, thus flexing 35 slightly the plate section. If the rim and hub portions were in one plane as is the case with the wheel, proper expansion of the rim portion would result in a direct pull upon the hub portion which would tend to weaken its press fit on the axle.

Upon the journal portion 34 is mounted a split or two-piece bronze sleeve 56. The structural brake carrier 20 is mounted directly on the bronze sleeve 56 and performs the several functions of 40 suspending the braking system, supporting the ends of the equalizer 10 in the pocket 13 as previously described, and engaging the pedestals 4 provided at the ends of the truck side frame 2. A wear surface is provided on the inner face of 45 the column 4 at 58, bearing against the wear-face 60 provided on the member 20 and these two surfaces may be lubricated through the opening or conduit 62 leading from the lubricant chamber 64.

55 Pedestal engaging flanges 66 on the brake carrier 20 serve to transmit lateral forces from the side frame 2 to the inner axle 6 through contact with the flanges 68 on the sleeve 56. The brake carrier 20 is secured in position over the sleeve 60 60 by a clamping cap 70 which is secured by the bolt and nut assemblies 72 and 74. The inner end of the brake carrier 20 is secured to the equalizer 10 through the medium of the spring seat member 22 by a structure shown in detail 65 in Figure 4.

The eye 76 is formed in the end of the brake carrier 20 in vertical alignment with the eye 26 of the spring seat member 22; and the members 20 and 22 are secured together by the bolt and 70 nut assembly 78. Resiliency in the connection is provided by heavy rubber washers 80 secured on either side of the eye member 76 between the caps 82 and the washers 84 and relative rigidity is provided between the two members by means 75 of the sleeve 86. The rubber washers 80 will

alternately be placed in compression as the inner end of the brake carrier 20 tends to rotate upwardly or downwardly, depending upon the direction of rotation of the wheel as the brakes are applied. The fulcrum point for this slightly rotational movement is of course the bearing point of the brake carrier 20 on the sleeve 56.

The dead lever 88 is supported through pivotal connection as at 90 from the outer end of the brake carrier 20 and the lower end of the dead 10 lever 88 is connected to the straps 92 through a pivotal connection as at 94 which is made adjustable by means of the plurality of holes 96 in the straps 92. At their inner ends the straps 92 have a pivotal connection as at 98 to the live 15 brake lever 100 which is suspended from the brake carrier 20 by the link 102 which is pivotally connected to the carrier 20 as at 104 and to the live brake lever 100 as at 106. The upper end of the live brake lever 100 is pivotally connected as at 20 108 to a push rod 110 which is operatively connected in the usual manner to a brake cylinder (not shown). This brake cylinder may be attached to the car body or secured to the truck 25 frame.

Brake shoes 112 and 114 are secured at intermediate points to the live brake lever 100 and the dead brake lever 88, respectively, by pivoting connections as at 116 and 118. The brake shoes 112 and 114 may be provided with the 30 flanges 120 to insure more positive alignment with the rim portion 55 of the auxiliary wheel or drum member 54.

In application of the brakes it will be apparent from the drawings and description that 35 actuation of the push rod 110 by the application of power to the cylinder associated therewith will give counter-clockwise rotation to the live lever 100 about the pivot point 106, thus applying the brake shoe 112 against the braking surface of the rim 55. Continued movement of the live lever 100 causes pivotal movement thereof about the point 116, moving the straps 92 to the right and rotating the dead lever 88 in a counter-clockwise direction about the pivot point 90 thus 40 applying the brake shoe 114 to the opposite side of the auxiliary wheel or drum member 54.

The brakes may be released by actuation of the push rod 110 in the opposite direction. This release movement may be accomplished by any 50 well known release mechanism or by the application of power to the brake cylinder in the reverse direction.

In Figures 6 and 7, I have shown my novel 55 brake equipment as applied to a friction type of wheel and axle assembly. The truck 122 is of conventional passenger type form, having the side rails 124 with pedestal columns 126 and 128 designed to cooperate with the associated journal box 130 which serves as a housing for the 60 journal end 132 of the axle 134. In order to simplify the structure shown, I have omitted showing in these figures the conventional form of equalizer similar to that shown in Figure 1, one end of which cooperates with the top of the 65 journal box at the point 135 and the other end of which is associated with an adjacent journal box in a similar manner as generally shown in the similar truck structure of Figure 1.

I may use the standard method of connecting 70 the journal box to the journal portion of the axle through a wedge and a journal brass (not shown), my purpose here being simply to show the method of associating my novel brake system with such a truck.

As shown, the wheels 136 are pressed upon the ends of the axle 134 and secured thereon by the usual press fit. I have shown a novel design of wheel having an elongated hub portion 138 machined on its outer surface for the reception of the drum or auxiliary wheel 140 provided for braking purposes. The brake drum 140 is somewhat similar in form to the wheel proper, having a hub portion 142, a plate portion 144 and the rim 146. The drum 140 may be pressed into position on the hub of the wheel in abutment against the shoulder 148. It will be understood, of course, that this drum might be pressed directly upon the axle 134 instead of as here shown upon the extended hub portion 138 of the wheel 136.

The dead truck lever 150 is pivotally hung as at 151 from the bracket 152 on the outer end of the truck frame and pivotally connected at a point intermediate its ends as at 153 by the straps 154 to an intermediate point of the opposing live truck lever 156 as at 158. The live truck lever 156 is pivotally connected at its upper end as at 160 to the pull rod 162 which may be actuated by the usual operating means such as a power cylinder (not shown). The hanger 164 is pivotally connected as at 166 to the side rail 124 and at its lower end is pivotally connected as at 168 to the brake head 170 which likewise is connected to the live lever 156 at the pivotal point 168. At the opposite side of the wheel the brake head 172 is pivotally connected as at 174 to the lower end of the dead lever 150, brake shoes 176 are associated with the brake heads and arranged for braking contact on the opposite sides of the braking drum 140. The brake heads and their associated shoes are held in proper adjustable relation to their respective brake levers and the associated wheel by the bracket arm 178 which houses the coil spring 180.

In operation, actuation of the pull rod 162 to the right as shown in Figure 6 by means of a power mechanism such as a brake cylinder (not shown) results in clockwise rotation of the live truck lever 156 about the pivot 158, forcing the brake head 170 and its associated shoe against the adjacent rim 146 of the brake drum 140. Further actuation causes a pivotal movement of the dead truck lever 150 in a counter-clockwise direction about the pivotal point 151, operative movement being transmitted from the live lever 156 to the dead lever 150 by means of the straps 154. This counter-clockwise movement of the dead lever 150 applies the brake head 172 and its associated brake shoe to the opposite side of the rim 146. Actuation of the pull rod 162 in the opposite direction by the power means referred to releases the brakes, moving the parts in the opposite direction to that just mentioned.

It is to be understood that I do not wish to be limited by the exact embodiments of the device shown, which are merely by way of illustration and not limitation, as various and other forms of the device will of course be apparent to those skilled in the art without departing from the spirit of the invention or the scope of the claims.

I claim:

1. In a railway truck, the combination of a truck frame including a side frame member and an equalizer, a wheel and axle assembly including an axle journal, a brake carrier secured at one end to said equalizer and mounted adjacent its opposite end on said journal, and brakes hung from said brake carrier.

2. In a railway truck, the combination of a truck frame including a side frame member and

an equalizer, a wheel and axle assembly including an axle journal, a brake drum mounted on said wheel and axle assembly, a brake carrier secured at one end to said equalizer and mounted adjacent its opposite end on said journal, and 5 brakes hung from said brake carrier.

3. In a railway truck, the combination of a truck frame including a side frame member and an equalizer, a wheel and axle assembly including an axle journal, a brake drum mounted on said wheel and axle assembly, a brake carrier secured at one end to said equalizer and mounted adjacent its opposite end on said journal, and 10 brakes hung from said brake carrier, said brakes including brake shoes supported at each side of 15 said drum for braking thereagainst.

4. In a railway truck, the combination of a truck frame including a side frame member and an equalizer, a wheel and axle assembly including an axle journal, a brake drum mounted on 20 said wheel and axle assembly, a brake carrier secured at one end to said equalizer and mounted adjacent its opposite end on said journal, and brakes hung from said brake carrier, said brakes including a live lever, a dead lever, and brake 25 shoes mounted intermediate the ends of said levers.

5. In a railway truck, the combination of a truck frame including a side frame member and an equalizer, a wheel and axle assembly including an axle journal, a brake drum mounted on 30 said wheel and axle assembly, a brake carrier secured at one end to said equalizer and mounted adjacent its opposite end on said journal, and brakes hung from said brake carrier, said brakes 35 including a dead lever supported at the outer end of said carrier, a live lever supported adjacent the opposite end of said carrier and straps connecting said levers.

6. In a railway truck, the combination of a truck frame including a side frame member and an equalizer, a wheel and axle assembly including an axle journal, a brake drum mounted on 40 said wheel and axle assembly, a brake carrier secured at one end to said equalizer and mounted 45 adjacent its opposite end on said journal, brakes hung from said brake carrier, said brakes including a dead lever supported at the outer end of said carrier, a live lever supported adjacent the opposite end of said carrier, straps connecting 50 the lower ends of said levers, and brake shoes mounted intermediate the ends of said levers.

7. In a railway truck, the combination of a truck frame including a side frame member and an equalizer, a wheel and axle assembly including 55 an axle journal, a brake drum mounted on said wheel and axle assembly, a brake carrier secured at one end of said equalizer and mounted adjacent its opposite end on said journal, brakes 60 hung from said brake carrier, said brakes including a dead lever supported at the outer end of said carrier, a live lever supported adjacent the opposite end of said carrier, straps connecting 65 the lower ends of said levers, and brake shoes mounted intermediate the ends of said levers for engagement with said drum.

8. In a railway truck, the combination of a truck frame including a side frame member and an equalizer, a wheel and axle assembly including 70 an axle journal, a brake drum mounted on said wheel and axle assembly, a brake carrier secured at one end to said equalizer and mounted adjacent its opposite end on said journal, brakes 75 hung from said brake carrier, said brakes in-

- cluding a dead lever supported at the outer end of said carrier, a live lever supported adjacent the opposite end of said carrier, straps connecting the lower ends of said levers, and brake shoes mounted intermediate the ends of said levers for engagement on opposite sides of said drum.
9. In a railway truck, the combination of a truck frame, a wheel and axle assembly including projecting axle ends, brake drums mounted on said assembly exteriorly of and adjacent the wheels thereof, brake carriers journaled on said axle ends and clasp brake means supported on said carriers.
10. In a railway truck, the combination of a truck frame, a wheel and axle assembly including a projecting axle end, a brake carrier journaled on said axle end and provided with lateral thrust flanges, said flanges serving as the sole means for transmitting lateral thrusts between said truck frame and said wheel and axle assembly.
11. In a railway truck, the combination of a truck frame, a wheel and axle assembly including projecting axle ends, brake drums mounted on said assembly exteriorly of and adjacent the wheels thereof, brake carriers journaled on said axle ends and clasp brake means supported on said carriers, said means including dead levers supported at the outer ends of said carriers, live levers supported adjacent the opposite end of said carrier, connections between said levers, and brake shoes carried intermediate the ends of said levers.
12. In a railway truck the combination of a truck frame comprising an equalizer, a brake carrier supported from said frame, a wheel and axle assembly including brake drums, and clasp brake equipment hung from said carrier and cooperating with said drums.
13. In a railway truck the combination of a truck frame comprising an equalizer, a brake carrier supported from said equalizer, a wheel and axle assembly including brake drums mounted exteriorly of the wheels, and clasp brake equipment hung from said carrier.
14. In a railway truck the combination of a truck frame comprising an equalizer, a brake carrier supported from said equalizer and having lateral thrust flanges, a wheel and axle assembly including brake drums, and clasp brake equipment hung from said carrier.
15. In a railway truck the combination of a truck frame comprising a side member, a brake carrier having one end supported therefrom from said member, a wheel and axle assembly including brake drums, and clasp brake equipment supported from said carrier and cooperating with said drums.
16. In a railway truck the combination of a truck frame comprising a side member, a brake carrier having an end supported from said member, a wheel and axle assembly including brake drums, and clasp brake equipment supported from said carrier, said drums being mounted on said assembly exteriorly of the wheels thereof.
17. In a railway truck, the combination of a truck frame, a brake carrier comprising thrust flanges and having an end supported from said truck frame, a wheel and axle assembly including brake drums, and clasp brake equipment supported from said carrier.
18. In a railway car truck the combination of a truck frame comprising a side member, a brake carrier having an end supported from said member, and clasp brake equipment hung from said carrier.
19. In a railway car truck, a truck frame comprising an equalizer, a brake carrier having an end supported from said equalizer, and clasp brakes hung from said carrier.
20. In a railway car truck the combination of a truck frame comprising an equalizer, a brake carrier supported from said equalizer, and a wheel and axle assembly having brake drums mounted thereon.
21. In a railway car truck, a truck frame comprising an equalizer, a brake carrier having an end supported from said equalizer, and a wheel and axle assembly including a brake drum mounted on said assembly exteriorly of the wheels thereof, said brake carrier having flanges for transmission of lateral thrusts between said assembly and said frame.
22. In a railway car truck the combination of a truck frame comprising an equalizer, a brake carrier having an end supported from said equalizer, and a wheel and axle assembly having brake drums mounted thereon outwardly of the wheels.
23. In a railway car truck the combination of a truck frame comprising an equalizer, a brake carrier having an end supported from said equalizer, and a wheel and axle assembly having brake drums mounted thereon outwardly of the wheels, said carrier having flanges for transmitting lateral thrusts between said assembly and said frame.
24. In a railway car truck the combination of a truck frame comprising a side member, a brake carrier having an end supported from said member, and a wheel and axle assembly having brake drums mounted thereon outwardly of the wheels.
25. The combination of a railway car truck comprising a truck frame, a brake carrier having an end supported from said frame, and a wheel and axle assembly having brake drums mounted thereon outwardly of the wheels, said carrier having flanges for transmitting lateral thrust between said assembly and said frame.
26. The combination of a railway car truck comprising a truck frame having an equalizer, a wheel and axle assembly having a projecting journal end, a brake drum mounted on said wheel and axle assembly, and a brake carrier supported at one end from said equalizer and adjacent its opposite end on said journal end.
27. The combination of a railway car truck comprising a truck frame having an equalizer, a wheel and axle assembly having a projecting journal end, a brake drum mounted on said wheel and axle assembly and brake supporting means supported at one end from said equalizer and adjacent its opposite end on said journal end, and clasp brake equipment supported from said carrier for cooperation with said drum.
28. The combination of a railway truck comprising a truck frame, a wheel and axle assembly, a brake carrier having an end supported from said truck frame and being supported adjacent its opposite end on said assembly, and clasp brake equipment supported from said carrier.
29. The combination of a railway truck comprising a truck frame, a wheel and axle assembly, a brake carrier having an end supported from said truck frame and being supported adjacent its opposite end on said assembly, and clasp brake equipment including live and dead levers supported from said carrier at opposite sides of said assembly.
30. In a railway car truck the combination of a truck frame comprising an equalizer, a brake carrier having an end supported from said equalizer.

izer, and clasp brake equipment hung from said brake carrier.

31. In a railway car truck the combination of a truck frame comprising an equalizer, a brake carrier having an end supported from said equalizer, and clasp brake equipment hung from said brake carrier, said brake equipment comprising live and dead levers, each of said levers having a brake head supported intermediate the ends thereof.

10 32. In a railway car truck the combination of a truck frame, a wheel and axle assembly, a brake carrier having an end supported from said frame and mounted on said assembly adjacent its opposite end, and clasp brake equipment hung from said carrier.

15 33. In a railway truck of the outboard type the combination of a wheel and axle assembly having projecting axle ends, a truck framework supported on said axle ends and comprising a side member, a member pivotally movable relative to said side frame, a brake disk mounted on said assembly exteriorly of and adjacent a wheel thereof, and clasp brakes supported from said movable member and operatively engaging the exterior surface of said disk on opposite sides thereof.

20 34. In a railway truck of the outboard type the combination of a wheel and axle assembly having projecting axle ends, a truck framework supported on said axle ends and comprising a side frame, a member pivotally supported in relation to said side frame, a brake disk mounted on said assembly exteriorly of and adjacent a wheel thereof, and clasp brakes supported from said member and comprising a dead lever, a live lever and brake shoes hung from each of said levers and engaging the perimeter of said disk.

25 35. In a railway truck of the outboard type the combination of a wheel and axle assembly having projecting axle ends, a truck framework supported on said axle ends and including a side frame, a member supported for pivotal movement relative to said side frame, a brake disk mounted on said assembly exteriorly of and adjacent a wheel thereof, and clasp brakes supported from said member and comprising a dead lever, a live lever and brake shoes hung from each of said levers and engaging the perimeter of said disk.

30 36. In a railway truck of the outboard type the combination of a wheel and axle assembly having

35 projecting axle ends, a truck framework supported on said axle ends and including a side frame, a member supported on said assembly for pivotal movement relative to said side frame, a brake disk mounted on said assembly exteriorly of and adjacent a wheel thereof, clasp brakes supported from said member and comprising a dead lever, a live lever, straps connecting said levers, and brake shoes hung from each of said levers and engaging the perimeter of said disk.

40 37. In a railway truck of the outboard type the combination of a wheel and axle assembly having projecting axle ends, a truck framework supported on said axle ends and comprising a side frame, a member supported on said assembly and having pivotal movement relative to said side frame, a brake disk mounted on said assembly adjacent a wheel thereof, clasp brakes supported from said member and comprising a dead lever, a live lever, and straps joining said levers inwardly and outwardly of said disks.

45 38. In a railway truck of the outboard type the combination of a wheel and axle assembly having projecting axle ends, a truck framework supported on said axle ends, a member supported on said assembly for pivotal movement relative to said framework, a brake disk mounted on said assembly, and clasp brakes supported from said member, said brakes including a live lever, a dead lever, straps connecting said levers, and brake shoes hung from said levers and engaging opposite sides of said disk.

50 39. In a railway car truck the combination of a wheel and axle assembly, a truck frame comprising a side frame, a member supported on said assembly for pivotal movement relative to said side frame, a brake drum supported on said assembly exteriorly of a wheel, and clasp brake equipment hung from said member and having cooperation with said drum.

40 40. In a railway car truck the combination of a truck framework including a side frame, a wheel and axle assembly, a member supported on said assembly for pivotal movement relative to said framework, a brake drum supported on said assembly exteriorly of a wheel, and brake equipment supported from said member and comprising brake heads and brake shoes applied to opposite sides of said drum.

ALFRED H. OELKERS. 50
